[57] CLAIM

The ornamental design for a workstation, as shown and described.

DESCRIPTION

FIG. 1 is a left, front perspective of a workstation showing our new design, with a top door and both bottom pedestals in open position;

FIG. 2 is a right, front perspective view thereof;

FIG. 3 is a front elevational view thereof;

FIG. 4 is a top plan view thereof; and,

FIG. 5 is a front elevational view in closed position.

The rear of the workstation and the interior of the closed door are not part of the claimed design.
